Primary Examiner — Ian Simmons*Assistant Examiner* — Samantha Q Lawrence(57) **CLAIM**

The ornamental design for a guidewire introducer apparatus, as shown and described.

DESCRIPTION

FIG. 1 is a perspective view of a guidewire introducer apparatus;

FIG. 2 is a bottom view of the apparatus of FIG. 1;
FIG. 3 is a top view of the apparatus of FIG. 1;
FIG. 4 is a right side view of the apparatus of FIG. 1;
FIG. 5 is a left side view of the apparatus of FIG. 1;
FIG. 6 is an enlarged rear view of the apparatus of FIG. 1; and,
FIG. 7 is an enlarged rear view of the apparatus of FIG. 1.
The broken lines shown in FIGS. 1-7 illustrate portions of the
guidewire introducer apparatus that form no part of the
claimed design.**1 Claim, 4 Drawing Sheets**FIG. 1

FIG. 2

FIG. 3

FIG. 4

FIG. 5

FIG. 7

FIG. 6
